(57) **CLAIM**

The ornamental design for a drinking mug handle, as shown and described.

DESCRIPTION

FIG. 1 is a perspective view of a drinking mug handle showing my new design;

FIG. 2 is a top plan view thereof;

FIG. 3 is a front elevational view thereof, the rear elevational view being a mirror image thereof;

FIG. 4 is a top plan view thereof, the bottom view being an identical view thereof; and,

FIG. 5 is a side elevational view thereof.

The broken line illustration of the mug in FIGS. 1-3 and 5 depict the environment in which the design resides and forms no part of the claim.
